Fig. 2

Fig. 4

Fig. 3

FIGURE 1 is a perspective view of a film inspecting machine embodying our new design;

FIGURE 2 is a front elevation of the machine;

FIGURE 3 is a top plan view of the machine; and

FIGURE 4 is an end elevation of the machine.

The back of the machine is plain and unornamented, and the end of the machine not shown is like the end illustrated in FIGURE 4.

The dominant features of the design reside in the portions shown in full lines.

We claim:

The ornamental design for a film inspecting machine, substantially as shown and described.
